Inventor:

Berthold A. Lange,

By Hugh X. Wagner

Attorney.

UNITED STATES PATENT OFFICE

BERTHOLD A. LANGE, OF ST. LOUIS, MISSOURI

BOX CORNER

Application filed November 26, 1926. Serial No. 150,840.

This invention relates to box-corners or joints in boxes that are formed of pasteboard, fiberboard, strawboard, or similar material. The invention has more particular reference to a novel form of flexible seam that is produced in the material by creasing the same, and on which the material can be bent to form a corner for a box.

An object of the invention is to provide a seam of the character described which will require less material to form a corner than the seams hitherto used in boxes of this character.

A further object is to provide a seam of such configuration that it can be creased in the blank of fiberboard or the like with a minimum strain on the material, and will, also, be sufficiently flexible to permit the stock to be bent readily thereon without fracture into box formation.

Other objects and advantages will appear in the course of the following description of a preferred embodiment of the invention.

In the accompanying drawing forming part of this specification, in which like numbers of reference denotes like parts wherever they occur:

Figure 1 is an end view of the sheet distended and after it has been removed from the dies;

Figure 2 depicts a box-corner embodying this invention; and

Figures 3 and 4 are end views which illustrate the pliability of this seam to flexure in respective opposite directions.

The illustrations depict end views of laminated fiberboard that has been creased to define the seam of this invention, but the invention can be embodied in other suitable sheet material, such, for instance, as cardboard, pasteboard, and the like.

The material is not scored, partly removed, or otherwise weakened to form the seam, but is upset without cutting away or breaking the fiber, and no more material than is neces-

sary for flexibility is gathered into the seam.

The creased sheet 13 presents the appearance shown in Figure 1, the seam comprising a pair of comparatively deep adjacent grooves 14 and 15 in the face 16 of the sheet, and a preferably shallower groove 17 in the other face 18 of the sheet intermediary of the grooves 14 and 15, whereby an intervening ridge 19 is presented on the face 16 that does not rise higher than the plane of the said face 55 or, better still, is disposed in retracted or depressed relation thereto, because the depression of the intermediate portion of ridge 19 of the seam facilitates bending as will be apparent from Figures 2 and 3, and the groove 60 17 and the width of the ridge 19 facilitate bending in the direction exhibited in Figure 4. The bottoms of the grooves 14, 15, and 17 can be round or of any other suitable shape, but the bottoms of the grooves 14 and 15 are 65 preferably substantially flat to bias the bending of the fibers thereat so that they readily assume the positions and directions depicted in Figure 3 when the sheet is bent in that direction.

Having thus fully described this invention, I hereby reserve the benefit of all changes in form, arrangement, order, or use of parts, as it is evident that many minor changes may be made therein without departing from the 75 spirit of this invention or the scope of the following claims.

I claim:

1. A sheet of material of the character described that is bent to define a flexible seam comprising, at least, a pair of adjacent flat-bottomed substantially square-cornered grooves in one face of the material and a ridge therebetween that presents a comparatively wide and substantially flat top face.

2. A laminated sheet of material of the character described that is bent and upset to define a flexible seam comprising a pair of adjacent flat-bottomed substantially square-cornered grooves in one face of the material 90

and a shallower groove in the other face of the material intermediary of the first-mentioned grooves, there being a ridge produced between said first-mentioned grooves and directly above said shallower groove, said ridge being wider than the adjacent grooves and presenting a substantially flattened top to facilitate bending of the material.

5 In testimony whereof I hereunto affix my
10 signature.

BERTHOLD A. LANGE.
